UNITED STATES PATENT OFFICE.

CHARLES HOTZE, OF ST. LOUIS, MISSOURI.

GOLF BAG.

Application filed October 12, 1925. Serial No. 62,047.

This invention pertains to golf bags and more particularly to the arrangement therein of a so called "Sunday bag".

One of the objects of this invention is to provide a Sunday bag which will be easily inserted and removed from the golf bag.

Another object is to provide a Sunday bag which will be securely retained in the golf bag when placed therein.

10 Further objects will appear from the following description taken in connection with the accompanying drawing in which:

Figure 1 is a vertical section of a golf bag embodying this invention, showing the Sunday bag mounted therein, and

Figure 2 is an enlarged detail showing the construction of the Sunday bag.

Referring to the accompanying drawing, 1 designates a golf bag of any suitable construction. This bag is usually constructed of heavy canvas suitably reinforced by vertical ribs and is provided usually with a metal rim 2 at the bottom upon which the bag may stand. Handles 3 and pockets 4 for carrying 25 balls and other auxiliary articles may be provided.

The upper end of the bag 1 is usually furnished with a substantial reinforcing rim. This may be of any suitable construction. In 30 the illustration, particularly in Figure 2, a curled metal rim 5 of aluminum or other suitable material is fixed to the upper part of the bag 1 and is reinforced by an outer rim 6 and an inner rim 7 held by rivets 8 or other suitable fasteners. The rims 5, 6, and 7 serve to reinforce and stiffen the mouth of the bag so that it will stand open.

Many golf bags are equipped with an inner Sunday bag 9 usually of much lighter 40 construction than the outer bag 1 but which may also be provided with a handle 10 and a pocket 11. The inner bag 9 is carried at times when it is inconvenient to carry the heavier outer bag and for the sake of convenience is usually arranged so that it may be placed within the outer bag as shown in Figure 1 when not used by itself.

In accordance with this invention, the inner bag 9 is provided at its rim with a reinforcing and stiffening hoop 12. This hoop 50 may be constructed of spring steel or other suitable resilient material so that it will hold the mouth of the bag open but at the same time be capable of flexure so that it may be sprung so as to pass through the mouth of the outer bag. This ring 12 may be attached

to the inner bag by inclosing same in a hem 13 at the rim of the inner bag. If desired, an extension hood 14 may be also provided so as to cover the golf clubs contained in the 60 bag by extending and closing the hood 14 as illustrated in Figure 1. The hood 14 is, however, not essential and may be omitted if desired.

When the inner bag is placed in the outer 65 bag the rim of the inner bag containing the hoop 12 is sprung to pass through the inner rim 7 of the outer bag. The diameter of the hoop is such that if passed through the rim 7 it will spring outwardly to the full inside 70 diameter of the outer bag. It may then be placed within the outer bag and underneath and adjacent the rim 7 as shown in Figure 2. In this position the rim of the inner bag will be retained in place by the rim of the outer 75 bag. This construction, therefore, provides a light and simple Sunday bag which may be quickly and easily inserted or removed from the outer bag and which when inserted will be retained in the outer bag.

When the extension hood 14 is used it may be extended over the golf sticks and secured at its mouth as illustrated in Figure 1 and in this position the inner bag is secured against removal from the outer bag, since 80 with the hood 14 extended the hoop 12 cannot be tipped from the position shown in Figure 2 so as to permit it to be sprung to pass through the rim 7. A reliable securing device is thus provided and after hood 90 14 is locked with a padlock, as is often done in such cases, the entire contents of the bag is securely locked therein. It will be seen, therefore, that the hoop 12 provides a resilient rim for the inner bag which not 95 only permits the removal thereof from the outer bag but which may be placed within the outer bag and adjacent the rim thereof and thus serve to retain the inner bag within the outer one.

It is obvious that various changes may be made in the details of construction without departing from the spirit of this invention; it is to be understood, therefore, that this invention is not to be limited to the 105 specific details shown and described.

Having thus described the invention, what is claimed is:

1. A combination golf bag, comprising, 110 an outer bag and an inner bag adapted to be nested together bottom to bottom, and a resilient ring on said inner bag adapted to

engage said outer bag in order to yieldingly retain said bags in nested relation.

2. A combination golf bag, comprising, an outer bag and an inner bag adapted to be nested together bottom to bottom, said inner bag having a resilient top rim adapted to engage said outer bag in order to yieldingly retain said bags in nested relation.

3. A combination golf bag, comprising, 10 an outer bag and an inner bag adapted to be nested together bottom to bottom, means for yieldingly retaining said bags in nested relation, and a hood attached to said inner bag.

15 4. A combination golf bag, comprising,

an outer bag having a rim at its open end, and an inner bag having a resilient rim at its open end, said bags being adapted to be nested together bottom to bottom with the rim of the inner bag engaging the rim of 20 the outer bag in order to yieldingly retain said bags in nested relation.

5. A combination golf bag, comprising an outer bag and an inner bag and means at 25 the top of said inner bag to frictionally engage the wall of the outer bag for retaining both of said bags in nested relation.

In testimony whereof I affix my signature this 15th day of September, 1925.

CHARLES HOTZE.
